UNITED STATES PATENT OFFICE.

FREDERICK H. HEATH AND JOHN R. NAGELL, OF TACOMA, WASHINGTON.

BOTTLE-SEAL.

SPECIFICATION forming part of Letters Patent No. 588,575, dated August 24, 1897.

Application filed September 18, 1896. Serial No. 606,257. (No model.)

To all whom it may concern:

Be it known that we, FREDERICK H. HEATH and JOHN R. NAGELL, citizens of the United States, residing at Tacoma, in the county of 5 Pierce and State of Washington, have invented a certain new and useful Improvement in Bottle-Seals, of which the following is a specification.

This present invention relates to an improved manner of securing a seal-tube in the neck of a bottle and the securing of a seal to the lower end of said tube, and has for its object to simplify and render more effective the operations of such a bottle.

With these ends in view this invention consists in the details of construction and combination of elements hereinafter set forth, and then specifically designated by the claims.

In order that those skilled in the art to which this invention appertains may understand how to make and use the same, its construction and operation will now be described in detail, referring to the accompanying drawings, forming a part of this specification, in

which—

Figure 1 is a section of the upper portion of a bottle, illustrating one embodiment of this invention and showing the seal secured in place in order that the contents of the bottle may not be withdrawn therefrom; Fig. 2, a section of a bottle, illustrating the appearance of the non-refilling device after the seal has been forced therefrom; Fig. 3, a side view of the seal-tube, the seal being in place upon said tube; Fig. 4, a plan of the resilient metal ring utilized as a keeper to secure the tube within the neck against removal therefrom; Fig. 5, a view similar to Fig. 1, illustrating a modification of this invention; and Fig. 6, an elevation of the seal-tube assembled for insertion within the neck of a bottle.

Referring to Figs. 1, 2, 3, and 4, A represents the seal-tube, having three annular grooves formed in the periphery thereof, the superior and inferior grooves adapted to receive the cork washers or rings B and C, and the intermediate groove, which is preferably semicircular in cross-section, is adapted to receive and retain the resilient ring D. The 45 resiliency of this ring is utilized by its ends being sufficiently separated to permit the 50 springing inward thereof when occasion re-

quires. A central opening E is formed through the tube of sufficient capacity to permit the ready outflowing of the contents of the bottle when no other obstruction is offered thereto, and it is preferable that the upper portion of this opening be flared, as clearly shown in Figs. 1 and 2. F represents the seal, which is here shown as hemispherical, and it is secured against the lower end of the tube, so as to close the opening therethrough by the ferrule G, whose upper edge is inturned, as indicated at H, so as to fit over the shoulder formed by the inferior annular groove in the tube, the bottom of said ferrule having formed thereon the serrations I, which when inturned, as shown in Figs. 1 and 3, support the seal and prevent its being removed, except by considerable pressure from above. A vent-hole J is formed in the lower edge of the seal-tube and corresponds with a similar hole formed in the ferrule in order that when the bottle has been filled and the tube forced into place it may be corked without unduly compressing the air within the opening E, said air escaping by the vent-hole to equalize the pressure above and below the seal. In practice this embodiment of this invention is forced within the neck of the bottle after the latter has been filled, and when the ring D registers with the groove K, formed in the interior of the neck of the bottle, said ring will spring outward, thereby sufficiently engaging said groove as to preclude the possibility of either withdrawing the tube or forcing it into the interior of the bottle, the cork rings B and C causing the device to fit snugly within the neck. After the tube has been forced into place the cork L may be utilized in the usual manner for stopping the mouth of the bottle.

Now when it is desired to gain access to the contents of the bottle or withdraw the same the cork L is removed and a punch or other suitable implement passed through the opening E and sufficient force exerted thereon to displace the seal by bending the serrations I outward, as clearly shown in Fig. 2, when said seal will be precipitated into the bottle, where it tends to prevent a fraudulent use of the bottle by refilling and selling as the original package. The advantage of this arrangement is that there is no liability of

particles of foreign substances, such as glass or the like, gaining access to the interior of the bottle when the latter is being unsealed.

In the modification shown in Figs. 5 and 6, 5 M represents the seal-tube, having a central opening N formed therethrough, and near the lower end of this opening is formed an annular groove for the reception of the cork ring O. This ring O is fitted to a corresponding annular groove formed in the seal P, which latter is preferably of glass and is provided with a shoulder Q, so that when it is forced within the lower end of the tube this shoulder will prevent it from passing beyond the proper 10 distance and cause the annular groove therein to register with the annular groove within the opening N, at which time the cork O will expand within the last-named groove, thereby firmly holding the seal in place against accident 15 removal, but will permit the forcing of said seal downward by a suitable implement, as before described. R and S are rings of cork or other suitable material fitted within grooves formed in the outer wall of the tube 20 and serve to hold said tube snugly in place within the neck of the bottle, and this tube is prevented from withdrawal from the neck by the keeper T, which is formed of sheet metal, having a number of prongs U projecting 25 upwardly and outwardly, so as to engage a suitable shoulder formed in the neck. The operations of this last-described embodiment of this invention are identical in all respects with those before described.

Having thus fully described this invention, 35 what is claimed as new and useful is—

1. A tube secured in the neck of a bottle, 40 a seal secured to the bottom by a ferrule having inturned serrations along its lower edge, substantially as described.

2. In combination with a bottle, a tube secured in the neck thereof, a ferrule secured to the lower part of the tube, inturned serrations formed around the lower edge of the ferrule and a seal adapted to be held against 45 the bottom of the tube by said serrations, as and for the purpose described.

3. A tube secured in the neck of a bottle, 50 said tube having an annular groove formed around the lower part, a ferrule secured to said tube by having its upper edge inturned to fit over the shoulder of the groove, inturned serrations formed around the lower edge of the ferrule, a hemispherical seal secured to the bottom of said seal by said serrations, 55 said tube having a vent-hole formed in the lower edge thereof and registering with a hole in the ferrule, as and for the purpose described.

In testimony whereof we have hereunto affixed our signatures in the presence of two subscribing witnesses.

FREDERICK H. HEATH.
JOHN R. NAGELL.
